[57] CLAIM

The ornamental design for adjustable light, substantially as shown and described.

DESCRIPTION

FIG. 1 is a perspective view of a adjustable light incorporating our new design;

FIGS. 2, 3, 4 and 5 are, respectively, front, left side, right side and rear elevational views thereof on an enlarged scale;

FIGS. 6 and 7 are, respectively, top and bottom plan views thereof on an enlarged scale;

FIG. 8 is a side elevational view thereof on a greatly enlarged scale, taken partly in section along planes corresponding to line 8—8 of FIG. 7;

FIG. 9 is a perspective view thereof on a reduced scale, the mounting panel being shown in broken lines for illustrative purposes only.

The characteristic features of our design comprise those elements which are exposed to view when in use, such as illustrated in FIG. 9.
